DESIGN FOR A MORTUARY CANDLE.

Application filed September 10, 1923. Serial No. 7,163. Term of patent 14 years.

To all whom it may concern:

Be it known that I, EVELYN L. KUHN, a citizen of the United States, and a resident of the city of New York, borough of Brooklyn, in the county of Kings and State of New York, United States of America, have invented a new, original, and ornamental Design for Mortuary Candles, of which the following is a specification, reference being had to the accompanying drawing, forming a part thereof, wherein—

Figure 1 represents a front view of a candle bearing my design; and

Figure 2 a projection or flat of my design showing it in its complete details.

The essential features of my design com-

prise an upper band ornamented with serrations and streamers, the band and streamers being of contrasting color, a Latin cross in solid color bordered by an edging in contrasting color, and a lower band in solid color surmounted by a series of rectangular links and bordered at the top and bottom by serrated bands, the said bands and links being of a color contrasting with the color of the said lower band.

What I claim and desire to secure by Letters Patent, is:

The ornamental design for a mortuary candle, substantially as shown and described.

EVELYN L. KUHN.
